UNITED STATES PATENT OFFICE

2,334,371

GARMENT HANGER

Leonard A. Young, Detroit, Mich.

Application April 10, 1942, Serial No. 438,465

9 Claims. (Cl. 223—92)

The main objects of this invention are:
First, to provide an efficient garment hanger employing a small amount of wire.

Second, to provide a garment hanger in which the yoke portion is formed of a paper tube which is strong and rigid and capable of carrying quite heavy loads.

Third, to provide a garment hanger comprising a non-metallic yoke portion and a wire hook portion in which the parts may be quickly assembled and the wire hook portion is assembled with the non-metallic portion in a manner that does not weaken the non-metallic portion.

Objects relating to details and economies of the invention will appear from the description to follow. The invention is defined in the claims.

Preferred embodiments of the invention are illustrated in the accompanying drawing, in which:

Fig. 1 is a side elevation of a garment hanger embodying my invention partially in vertical longitudinal section and partially broken away to show structural details.

Fig. 2 is an enlarged fragmentary view on a line corresponding to line 2—2 of Fig. 1.

Fig. 3 is a fragmentary view partially in vertical longitudinal section on a line corresponding to line 3—3 of Fig. 4 of a modified form of my invention.

Fig. 4 is an enlarged fragmentary view in section on line 4—4 of Fig. 3.

Fig. 5 is a fragmentary view partially in vertical longitudinal section showing another modified form or embodiment of my invention.

Referring to the drawing, my garment hanger comprises a yoke 1 having downwardly diverging arms 2, this yoke in the preferred embodiment of my invention being formed of a paper tube. The ends of the arms 2 are vertically collapsed and downwardly curved to provide shoulder portions 3. The apex 4 of the yoke is curved and the under-wall 5 thereof is collapsed upwardly centrally thereof providing a longitudinal groove-like recess 6 of substantial arc. The ends 3 are collapsed and curved or conformed and this under-wall portion 5 is collapsed in the preferred process of manufacture quite promptly after the tube is formed and before the glue or adhesive used in forming the tube has set, the yoke being conformed to its general yoke-shape at the same time.

The tube is formed of a plurality of layers or plies of paper as is conventionally shown in Fig. 2.

The yoke is provided with a hole or opening 55

7 at the apex thereof receiving the shank 8 of the suspending hook 9 formed of wire of suitable gauge. At the lower end of the shank, the wire is conformed to provide oppositely disposed loop-like arms 10 which in effect constitute a cross member for the hook engaging within the recess 6, the upper arm portions 11 of the loop arms being curved to correspond to the curvature of the yoke at the apex thereof. The suspending hook with its arms or cross portion thus serves as a reinforcing means for the body or yoke portion of the hanger. The arms being engaged in the recess prevent twisting or turning of the hook relative to the yoke. The hole 7 is preferably of such size as to frictionally engage the shank and thereby prevent accidental shifting of the hook.

In the embodiment shown in Fig. 5, the shank 12 of the hook is formed of twisted strands so that the hook may be engaged by a turning or screwing motion which prevents the shank accidentally shifting in the yoke.

In the embodiment of my invention shown in Fig. 3, the shank 13 which is also formed of twisted strands has spaced portions 14 at the lower end thereof. The yoke in this embodiment has spaced holes 15 through the apex thereof with a connecting slit 16 disposed so as to provide a tongue 17 between the holes. When the hook is engaged with the yoke as shown in Figs. 3 and 4, the tongue 17 springs or snaps between the shank members 15 and thus serves as a retaining means.

My improved garment hanger may be formed of relatively light material and at the same time is quite strong and rigid, one of the objects being to conserve material and at the same time provide an efficient garment hanger. It has sufficient strength so that it may be used for men's suits, the legs of the trousers being draped over the arms and the vest and coat superimposed thereon. It is obvious of course that it may be used particularly where garment hangers are desired which do not have cross struts.

I have illustrated and described my improvements in what I regard as a very practical embodiment thereof. I have not illustrated or described certain other embodiments or adaptations as it is believed that this disclosure will enable those skilled in the art to embody or adapt my improvements as may be desired.

Having thus described my invention, what I claim as new and desire to secure by Letters Patent is:

1. In a garment hanger, the combination of a

supporting yoke formed of paper tube and having downwardly diverging arms terminating in vertically collapsed and downwardly curved end portions, the apex of the yoke being curved and the under-wall thereof being upwardly collapsed centrally thereof to provide a downwardly facing longitudinal recess of substantial arc, there being a central opening through the apex, and a suspending hook provided with a shank arranged through said opening and having oppositely disposed loop-like arms at its lower ends, the upper portions of the arms being curved to engage within said recess, said arms constituting supporting and reinforcing members for the yoke.

2. In a garment hanger, the combination of a supporting yoke formed of paper tube, the apex of the yoke being curved and the under-wall thereof being upwardly collapsed centrally thereof to provide a downwardly facing longitudinal recess of substantial arc, there being a central opening through the apex, and a suspending hook provided with a shank arranged through said opening and having oppositely disposed loop-like arms at its lower ends, the upper portions of the arms being curved to engage within said recess, said arms constituting supporting and reinforcing members for the yoke.

3. In a garment hanger, the combination of a supporting yoke of tubular section and having downwardly diverging arms, the under-wall of the apex of the yoke being upwardly collapsed and conformed to provide a downwardly facing longitudinal recess, there being a central opening through the apex, and a suspending hook provided with a shank disposed through said opening and having a cross portion engaged within said recess.

4. In a garment hanger, the combination of a supporting yoke of tubular section and having downwardly diverging arms, the under-wall of the apex of the yoke being upwardly collapsed, there being a central opening through the apex, and a suspending hook provided with a shank disposed through said opening and having at its lower end a cross portion engaging said collapsed wall.

5. In a garment hanger, the combination of a supporting yoke having downwardly diverging arms, the apex of the yoke being curved and having a central opening therethrough and having a downwardly facing longitudinal recess of substantial arc longitudinally of the yoke, and a suspending hook provided with a shank arranged through said opening, said shank having at its lower end oppositely disposed arms curved to engage within said recess and constituting supporting and reinforcing members for the yoke, said recess being of substantially the same width

as said arms to retain said yoke against lateral movement relative to said arms.

6. In a garment hanger, the combination of a supporting yoke having downwardly diverging arms, the apex of the yoke having a central opening therethrough and having a downwardly facing longitudinal recess, and a suspending hook provided with a shank arranged through said opening, said shank having at its lower end a cross member engaged within said recess, said recess being of substantially the same width as said cross member to retain said yoke against lateral swinging movement relative to said cross member.

15 7. In a garment hanger, the combination of a tubular non-metallic supporting yoke having downwardly diverging arms, the under-wall portion of the yoke being collapsed upwardly at the apex and conformed to provide a longitudinal downwardly facing groove-like recess, the collapsed and top wall of the yoke having spaced holes therein connected by a slit disposed to provide a tongue intermediate the holes, and a wire supporting hook provided with a shank disposed through said holes and terminating in opposed supporting arms engaging within said recess of said yoke, said shank having spaced strands at the base thereof disposed in said spaced holes with said tongue between the strands and constituting retaining means for the hook.

20 8. In a garment hanger, the combination of a supporting yoke of tubular section having downwardly diverging arms, the under-wall of the apex of the yoke being upwardly collapsed, there being opposed shoulders at the ends of said upwardly collapsed portion and there being a central opening through the apex, and a suspending hook provided with a shank arranged through said opening and having oppositely disposed loop-like arms at its lower ends, the upper portions of the arms engaging the under side of the collapsed portion and the ends of the arms engaging said opposed shoulders at the ends of the collapsed portion.

25 9. In a garment hanger, the combination of a supporting yoke of tubular section having downwardly diverging arms, the under-wall of the apex of the yoke being upwardly collapsed, there being opposed shoulders at the ends of said upwardly collapsed portion and there being a central opening through the apex, and a suspending hook provided with a shank arranged through said opening and having a cross portion engaging the under side of the collapsed portion, its ends engaging said opposed shoulders at the ends of the collapsed portion.
